Patented Sept. 23, 1969

215,388

LIPSTICK BLENDING MACHINE

Lewis J. Kieran, 511 Montview Place,
Pittsburgh, Pa. 15221

Filed Apr. 19, 1968, Ser. No. 11,534

Term of patent 14 years

Int. Cl. D28—99

U.S. Cl. D86—10

Fig. 1.

Fig. 2.

*Fig. 5.**Fig. 3.**Fig. 4.*

FIGURE 1 is an isometric view taken from the front and one side of a lipstick blending machine showing my new design;

FIGURE 2 is an isometric view taken from the rear and side opposite that shown in FIGURE 1;

FIGURE 3 is a front elevational view thereof;

FIGURE 4 is a rear elevational view thereof; and

FIGURE 5 is an isometric view taken from the rear and one side of a modified form of the lipstick blending machine shown in FIGURE 1.

I claim:

The design for a lipstick blending machine, substantially as shown and described.
